UNITED STATES PATENT OFFICE.

LEWIS S. BROWN, OF COLUMBUS, OHIO, ASSIGNOR TO LEWIS S. BROWN
AND WILLIAM W. BUCKLEY, OF SAME PLACE.

DESIGN FOR A GAS-BURNER.

SPECIFICATION forming part of Design No. 33,106, dated August 21, 1900.

Application filed July 3, 1900. Serial No. 22,455. Term of patent 14 years.

To all whom it may concern:

Be it known that I, LEWIS S. BROWN, a citizen of the United States, and a resident of Columbus, in the county of Franklin and State of Ohio, have invented and produced a new and original Design for a Gas-Burner, of which the following is a full, clear, and exact description.

Reference is to be had to the accompanying drawings, forming a part of this specification, in which similar characters of reference indicate corresponding parts in both the figures.

Figure 1 is a perspective view of a burner embodying my new design, and Fig. 2 is a plan view thereof.

The leading feature of the design consists in the configuration of the gas-burner made the subject of the accompanying illustrations.

The design presents a body A in the form of an annulus, the exterior wall or periphery *a* of which is convexed from the bottom toward the top, curving inward at the top, as at *a'*, to near the exterior surface *b* of the verti-

cal inner wall B of the annulus. Said inner wall B defines the eye or through-opening C 25 of the annulus, and it rises to a point above the top *a'* of the exterior wall *a*, and at the upper end of the inner wall B is a lateral flange *b'* of circular form, which overhangs the top *a*, as shown. At the bottom of the 30 eye appears a flange *a''*, as seen in Fig. 2. At one side of the body A is a neck D, which projects laterally and has a foot *d* at the under side.

Having thus described my invention, I 35 claim as new and desire to secure by Letters Patent—

The design for a gas-burner, as herein shown and described.

In testimony whereof I have signed my 40 name to this specification in the presence of two subscribing witnesses.

LEWIS S. BROWN.
